UNITED STATES PATENT OFFICE.

JOSEPH NOGUER-USALL, OF NEW HAVEN, CONNECTICUT.

MACHINE FOR SORTING HAIR.

1,090,560.

Specification of Letters Patent.

Patented Mar. 17, 1914.

Application filed November 11, 1912. Serial No. 730,650.

To all whom it may concern:

Be it known that I, JOSEPH NOGUER-USALL, a citizen of the United States, residing at New Haven, in the county of New Haven 5 and State of Connecticut, have invented a new and useful Improvement in Machines for Sorting Hair; and I do hereby declare the following, when taken in connection with the accompanying drawings and the characters of reference marked thereon, to be a full, clear, and exact description of the same, and which said drawings constitute part of this application, and represent, in—

Figure 1 a top or plan view of a machine for sorting hair constructed in accordance with my invention. Fig. 2 a front view of the same. Fig. 3 a side view. Fig. 4 a transverse sectional view. Fig. 5 a plan view of the upper pad holder detached. Fig. 6 a plan view of the lower pad holder detached. Fig. 7 a side view partially in section of the pad core. Figs. 8 and 9 are diagrammatic views showing the operation of the machine.

This invention relates to an improvement in machines for sorting hair, that is, a machine which will separate a bunch of hair into two sections each of which leaves the root ends all in the same direction.

In the manufacture of false hair, and particularly the manufacture of wigs, it is necessary that the ends of the hair which are fastened should be the root ends of the hair. In the usual method of sorting hair, it is done entirely by the sense of feeling, the hair having fiber which extends in one direction so that with a very fine sense of feeling by drawing the hair through the fingers the root end can be determined.

The object of this invention is to provide a machine which will sort hairs and thus enable the operator to sort them with much greater rapidity than can be done with the fingers; and the invention consists in the construction hereinafter described and particularly recited in the claims.

In carrying out my invention, I employ two parallel friction pads the lower pad 2 being mounted upon a shaft 3 fixed against rotation, but adapted to be moved up and down between guides 4 in posts 5 mounted upon a table 6 which is suitably supported by legs 7, the ends of the shaft being forced upward by springs 8 adjusted by screws 9. Parallel with the shaft 3 is a rock shaft 10

one end being pivoted to a shaft 11 which is provided with a slotted rocking arm 12. The other end is mounted in a socket 13 slidably mounted in the post 5 and a supporting bracket 14. On the socket is a finger-piece 15 by which it may be moved, and between the bracket 14 and the finger-piece is a spring 16 which tends to crowd the socket onto the rock-shaft 10. 60

On the rock shaft 10 is a pad 17. These pads 2 and 17 each comprise a central core 18 of metal surrounded by rubber or similar material 19 and located in the center of the shafts which are slotted to receive them and in which they are held in place by screws 70 23, and these in turn are inclosed by a jacket 20 of cloth, rubber, leather or other suitable material, and the relative position of the pads is such that their parallel edges will stand close together. As a convenient means 75 for holding these jackets and to permit of their being renewed when required, the edges of the jackets are folded about wire rods 21 the ends of which are hooked over lugs 22 mounted on the said shafts. The curve of 80 the frictional working surface of each pad is, as shown, struck on a smaller radius than the radius of the motion of the curved working surface of the rocking pad, so that owing to the fact that one pad is only mov- 85 able vertically and normally lies in the path of the other pad, and the other pad has a movement across the surface of the vertically movable pad and depresses the vertically movable pad as it passes over it, the 90 plane of tangency between the two pads is constantly changing during the swinging or rocking motion of the upper pad. The rock shaft 11 is oscillated, by connecting the slotted arm 12 by a link 24 with a crank 25 on 95 a shaft 26 carrying a pinion 27 meshing with a gear 28 on a driving shaft 29, this gear being driven by a crank handle 30, or it may be driven by power otherwise applied. 100

Forward of and parallel with the shafts 3 and 10 are two combs 31, 32, each adjustably mounted at the upper ends of comb arms 33, 34. These arms are respectively connected with cranks 46, 47, on the driving 105 shaft 29, and the lower ends of the arms are adjustably mounted in sockets 35 pivotally connected at the ends of links 36 which are mounted on an adjusting shaft 37 carried by the upper end of links 38 which are piv- 110

oted at 39 to the frame of the machine. The ends of the shaft 37 extend through segmental clearance slots 40 and are adapted to be locked in different positions of adjustment by a thumb nut 41. The connection of the comb with the driving shaft is such that as the driving shaft rotates the combs will describe a closed curve, moving upward against the pads and then rearward 5 to the limit of their excursion, then downward and upward against the pads.

To provide for moving the lower or stationary pad away from the upper pad, and so stop the operation of the machine, hooks 15 42 are connected with the lower shaft and the lower ends of these hooks united by a coupling bar 43 which is connected at the center by a link 44 with a latch 45. A bunch 20 of hair is first combed out so that the hairs stand substantially parallel with each other and the hairs at one end even and fastened by a string and the bunch soaped. The latch 15 is then moved outward to disengage the socket 13 from the end of the upper shaft 25 10 so that that shaft may be turned upward away from the lower pad. The hairs are then placed over the lower pad and the upper pad returned to a position parallel with it where it is held by the socket 13. Motion 30 is then imparted to the driving shaft 29 and this motion through the gears and the links 24 and 12 oscillates the upper pad across the upper edge of the lower pad which is held in contact with it by the springs 8. 35 This oscillating movement of the upper pad across the upper edge of the lower pad and across the hairs between them will separate the hairs the points of which are in rear of the pads from the hairs having root ends in 40 rear of the pads, and this operation continues until all the hairs with the points extending rearward will be withdrawn or moved forward away from the roots extending rearward. The oscillation of the combs 45 keeps these separated hairs from snarling. When the hairs are sufficiently separated, the pad 17 is swung away from the lower pad and the hairs removed. The root ends of the hairs extending in one direction are 50 then grasped and the hairs easily separated from the remaining mass. The remaining hairs necessarily stand in the same direction and are readily combed.

The operation will be clearly understood 55 from the diagram shown in Figs. 8 and 9. Fig. 8 shows the hairs as first placed in the machine, some of the roots on one side of the pads and the roots of the remaining hairs on the opposite side. Fig. 9 shows the 60 position after the operation has taken place

in which the roots are driven away from the pads.

It will be noted that the combs are so adjusted as to start operation at the lower pad just before the upper pad moves rearward 65 across the hairs. In other words, the action of the comb is in advance of the rearward pushing of the upper pad.

I claim:—

1. A machine for sorting hair having two 70 pads arranged one above the other each provided with a narrow, curved, frictional contacting surface, one pad limited to vertical movement, means for moving the frictional surface of the other pad tangentially across 75 the frictional surface of the vertically movable pad which normally stands in the path of the second named movable pad.

2. In a machine for sorting hair, the combination of two pads having narrow curved 80 frictional surfaces, means for rocking one of the pads, the frictional surfaces of the pads having smaller radii than the radius of the motion of the curved surface of the rocking pad. 85

3. In a machine for sorting hair, the combination of two pads one above the other, means for rocking the upper pad, means for exerting an upward pressure on the lower pad, each pad provided with a curved frictional surface, said surfaces being maintained in contact for a portion of their extent by said upward pressure, said curved surfaces each having a smaller radius than the radius of the motion of the contacting 90 portions of said rocking pad whereby the plane of the tangency of the two pads is constantly changed during the time of operation. 95

4. In a machine for sorting hair, the combination of two pads, one pad mounted above the other, a pair of comb-arms carrying combs at their upper ends, said combs arranged parallel with the axes of and on one side of said pads, a driving shaft, connections between the driving shaft and pads, whereby the upper pad will sweep back and forth across the upper edge of the lower pad, and crank and link connections between the driving shaft and comb arms whereby the 110 combs successively describe closed curves moving away from the lower edge of the upper pad. 105

In testimony whereof, I have signed this specification in the presence of two subscribing witnesses. 115

JOSEPH NOGUER-USALL.
